ATTORNEY

UNITED STATES PATENT OFFICE.

CARL EMIL LIEDBERG, OF CHICAGO, ILLINOIS.

DESIGN FOR A PARASOL.

47,246.

Specification for Design.

Patented Apr. 20, 1915.

Application filed April 30, 1913. Serial No. 764,695. Term of patent 7 years.

To all whom it may concern:

Be it known that I, CARL EMIL LIEDBERG, a citizen of the United States, residing at 327 West Goethe street, Chicago, in the county of Cook and State of Illinois, have invented a new, original, and ornamental Design for Parasols, of which the following is a specification, reference being had to the accompanying drawing, forming a part thereof.

The figure is a perspective of a parasol, showing my new design.

I claim:

The ornamental design for a parasol, as shown.

CARL EMIL LIEDBERG.
